DIVAN-BED.

1,180,311.

Specification of Letters Patent. Patented Apr. 25, 1916.

Application filed March 25, 1912. Serial No. 686,090.

To all whom it may concern:

Be it known that I, ROYAL R. MILLER, a citizen of the United States, and a resident of the city of Chicago, in the county of Cook and State of Illinois, have invented certain new and useful Improvements in Divan-Beds; and I do hereby declare that the following is a full, clear, and exact description of the same, reference being had to the accompanying drawings, and to the numbers of reference marked thereon, which form a part of this specification.

Davenport beds have usually been made of bed length longitudinally of the davenport frame; and the desired bed width has been obtained by opening or folding the mattress fabric outwardly in one or more folds. The requisite wall space in many rooms is not adapted for the installation of a long davenport in such room, and many attempts have been made to afford a relatively short davenport or divan, the length of which corresponds with the width of the desired bed, and the length of the bed is afforded by extending the mattress frame outwardly to the desired distance in advance of the main frame to afford the required bed length. To accomplish this, a mattress frame so constructed as to permit ready and convenient insertion in relatively narrow sections into the divan frame, is required, and a construction whereby the mattress or bed frame may be conveniently and safely supported in a horizontal plane when extended for use as a bed.

With this in view, it is an object of this invention to afford a short davenport or divan of the class described, wherein the mattress or bed frame is adapted to fold within or onto the bottom of the seat frame and together therewith, to be invertible into, or outwardly from, the davenport frame in opening or in closing the bed.

It is also an object of the invention to afford a construction whereby the folded mattress frame and bedding may be securely locked in folded position on the under side of the seat frame to permit the same to be carried inwardly by, and supported on the seat frame when the seat is at normal position, and adapted to be shifted outwardly and supported in folded position on the seat frame when the seat frame is inverted.

It is an important object of the invention

to afford an improved means for locking the bed and its bedding in closed position, and to afford in connection therewith a foot-board for a bed such as described whereby the bedding may be securely retained from slipping or sliding from the bed.

The invention embraces numerous novel features and (in its preferred form) is illustrated in the drawings and hereinafter more fully described.

In the drawings: Figure 1 is a top plan view, broken away, of a short davenport embodying my invention, and showing the same open. Fig. 2 is a side elevation thereof, with one of the arms of the frame and the cam plate omitted, and with the bed extended. Fig. 3 is a similar view, showing the bed in the process of closing inwardly upon the inverted seat frame. Fig. 4 is an enlarged view similar to Figs. 2 and 3, but showing the mattress frame and bedding folded upon, and secured to the under side of the seat frame and with the seat frame inverted. Fig. 5 is a reduced view similar to Figs. 2 to 4 inclusive, and showing the seat frame reverted to normal position, with the folded mattress and bedding supported thereon and therebeneath. Fig. 6 is an enlarged, fragmentary detail face view taken at the inner side the adjusting and locking plates, and partly in section, and showing the parts in normal position for use of the divan as a seat. Fig. 7 is a similar view, illustrating the position assumed by the parts during the turning or inversion of the seat preparatory to opening the bed frame. Fig. 8 is a similar view, illustrating the further turning or inversion of the seat frame. Fig. 9 is a similar view, with the seat fully inverted, as shown in Fig. 4. Fig. 10 is an enlarged, fragmentary section on line 10—10 of Fig. 2. Fig. 11 is an enlarged, fragmentary section on line 11—11 of Fig. 2. Fig. 12 is an enlarged section taken on line 12—12 of Fig. 9. Fig. 13 is an inner face view of the stationary cam and locking plate. Fig. 14 is an enlarged detail view of the foot-board or end of the bed taken on line 14—14 of Fig. 2.

As shown in the drawings: A main davenport frame constructed of the desired length and comprising end members 1, and a back 2, is constructed in any suitable manner to afford the requisite strength, and the

back (or, if preferred, the back and ends) are upholstered from the top downwardly to a point sufficiently low to coincide with the position of the seat when in normal position, as shown in Fig. 5. A back wall below the upholstered back, may be omitted, if desired, and from the construction described, it will be obvious that a front wall or rail connecting the ends or arm members 10 of the davenport frame, is not required.

Secured on each end member 1, is a cam and locking plate 3, which is attached thereto by bolts or otherwise, at or near seat height, and is provided, as shown, near its 15 bottom with a substantially horizontally extending slot A, therein, which extends for a considerable portion of the length of said cam and locking plate, and thence inclines slightly upwardly and then downwardly, 20 affording a forward extension of said slot, indicated by a. Extending obliquely and forwardly from said slot A, near the middle portion thereof, and through the edge of said cam and locking plate, is a guide or 25 cam slot B, the rear side of which is approximately straight, and the forward side of which is convexly curved, as shown in Figs. 6 to 9 inclusive, and near the top of 30 said plate the same is slotted horizontally, so that the slot B, at its top may communicate in a slot C, near its forward end and inclines upwardly therefrom at a less angle than the slot B, to near the forward end of 35 the plate, and thence substantially vertically upward. The web or cam rib 4, between the slots B and C, is substantially straight on its forward edge or that adjacent the cam slot C, and at the upper end thereof is rounded, while the lower rearwardly 40 extended end thereof is brought to substantially a point. As shown, said centrally inclined cam rib 4, is rigidly secured and spaced from the remaining portions of the plate by means of outwardly arching ribs 45 5, integrally connected with both, as shown in Fig. 13. Rigidly secured on the inner face centrally, and near the forward end of said guide and locking plate, is a pin 6, having a roller secured thereon, as shown in 50 dotted lines in Figs. 6 to 9, and 13.

7 indicates the seat frame, which is upholstered in the usual or any suitable manner, and rigidly secured on each end of which is a pivot plate 8, having set therein 55 at the outer side thereof and near the bottom and forward end, a pin or cap screw 9, having a headed roller 10, thereon, adapted to engage in the respective slots in the cam and locking plate to assist, and to support 60 the seat and the mattress frame and bedding in turning from or to normal position. Also secured on said plate and centrally thereof, but in horizontal alinement with the pin 9, and roller 10, is a pin 11; having a 65 roller 12, secured thereon and also movable

in the grooves or slots in the cam and locking plate. As shown also, the rear end of the pivot plate 8, is inclined or rounded upwardly near its extremity, and recessed to afford a hook, indicated by 13, adapted to engage over the pin 6, in the cam, and locking plate, when the seat is in normal position, as shown in Figs. 5 and 6. The relative position of said respective pins and rollers on said respective plates is such as to 70 permit the davenport seat to be overturned or inverted rearwardly, at which time the respective pins and rollers 9 and 10, and 11 and 12, serve as pivot pins and guide pins respectively as they move along the grooves 80 in the cam and locking plates at each end of the bed, to permit the turning movement. Said pins also serve as locks, as hereinafter more fully described, to rigidly hold the seat in either its normal or in its inverted 85 position until adjusted by the operator, as illustrated in Figs. 6 to 9 inclusive, and as hereinafter more fully described.

A fall or front board 14, is provided on the front side of the seat frame, which serves 90 to conceal the folded mattress frame and bedding when the device is closed, as shown in Fig. 5, and serves as a relatively low head-board when the bed is extended, as 95 shown in Figs. 1 and 2.

Secured on each end of the seat frame and projecting downwardly at each rear corner thereof, is a bracket or standard 15, the rear edge of which (when the seat is at normal) is substantially in alinement 100 with the back of the seat frame. Rigidly secured on the under side the seat frame and centrally and at each end thereof, is a slotted bracket 16, the slot in which extends from near the bottom and rear edge thereof and extends obliquely downwardly and forwardly, as shown in Fig. 5, and at its lower end extends substantially horizontally and forwardly, affording an offset or shoulder at the extremity of the slot.

The mattress frame is shown constructed in five alternately long and short sections, comprising an inner long section 17, having a pin and roller 18, set near the middle thereof and centrally and engaging in the 115 inclined slot in the slotted bracket 16, as shown in Figs. 2, 3, and 11. Said mattress frame 17, is articulated with a relatively short frame section 19, as shown eccentrically pivoted upon the bracket 15, near the 120 outer end of said short sections and by means of a downwardly curved brace or tie bar 20, which extends transversely the mattress frame and connects the opposite sides thereof at such short sections. Articulated with the outer ends (which afford the shorter leverage of the short sections 19) is the second long mattress frame section 21, and secured to the inner end of each of the 125 end frame members for the shorter sections 130

and to the inner end of said longer sections 21, are pulling springs 22, which extend outside the brace bar 20, and exert upward tension on both. Articulated with the outer 5 ends of the second long mattress frame section 21, and connecting therewith the outer long frame section 23, is the second short mattress frame section 24, which is articulated to permit the longer frame sections to 10 fold together beneath the same, as shown in Figs. 3 and 4. In a like manner, a downwardly curved brace or tie bar 25, shown in dotted lines in Figs. 2 and 3, connects the end frame members of said short frame section, and a corresponding bar 26, connects the outer end of the second long frame sections adjacent thereto.

As shown in dotted lines in Fig. 3, and in full lines in Fig. 4, the ends 27, of the short bed frame section 24, are extended beyond the pivot at the bottom of said frame section, so that the flange at said extended end engages on the flange of the long sections 21 and 23, to rigidly brace said sections in position when fully extended, as shown in Figs. 1 and 2. A leg 28, is pivotally engaged at the outer end of the outer mattress frame section 23, and is of a length to suitably support the same on the floor. The 25 upper end of said leg extends above the pivotal engagement of said mattress frame section, and is connected at its extremity by means of a bar 29, with the short link 24, near the middle thereof, as indicated in Figs. 2 and 3, so that the upward folding of the mattress, as shown in Fig. 3, acts to automatically swing said leg to closed position. A foot-board comprising a rod 30, bent to pivotally engage at its ends through the 30 webs of the outer mattress frame section at the outer end thereof, and oppositely, as indicated at 31, to bear upon the web of the end rail for said mattress frame section when elevated, as shown in Fig. 2, is shaped intermediate its ends to afford an ornamental foot piece for the bed, and at each side thereof is bent to afford a relatively straight outwardly projecting portion 32, which extends beyond the sides of the mattress 35 frame. A bottom bar 33, is rigidly connected near the ends of said rod 30, and vertical rods, tubes or bars 34, are engaged to said bar 33, and the substantially horizontal top 35, of said foot piece, although, 40 of course, the particular configuration of the foot piece and the general construction thereof may vary through a wide degree. Secured on the bottom of the seat frame, and as shown, adjacent to, and at the outer 45 side of the bracket 16, is a spring arm 36, provided with a hook 37, at its extremity, and an outwardly directed finger piece 38, integral therewith at the extremity. Said hook 37, is adapted to engage over the laterally offset portion 32, of the foot-piece when

the bed is closed, as shown in Fig. 4, to lock the mattress frame and its bed in closed position.

The operation is as follows: When the bed is closed in the position shown in Fig. 5, the mattress frame, with its bedding, is folded upon the seat frame and is suspended therebeneath on the bracket 16, engaging the short mattress frame section 19, and upon the hook 37, which engages the foot piece. 70 In this position the seat frame is rigidly locked in upright position by the engagement of the hook 13, of the plate 8, on the pin 6, on the cam and locking plate, the roller 10, on said plate being at the rear 75 extremity of the slot A, in said cam and locking plate, while the roller 12, secured on the pin 11, on said plate, bears beneath the downwardly and rearwardly inclined extremity of the rib 4, thus firmly locking 80 the seat frame and the supported mattress frame and bedding in upright posititon. In this position, the fall board 14, extends sufficiently low at the front of the seat to conceal entirely the mattress frame and bedding supported beneath the seat. When it is desired to open the bed, the front edge of the seat frame is lifted and drawn slightly forwardly, bringing the roller 12, on the pin 11, into the cam slot C, in the cam plate, as 85 shown in Fig. 7, while the roller 10, on the pin 9, permits the seat frame with its load to be inverted, said roller passing forwardly into the forwardly and downwardly inclined slot a, at the front end of the cam 90 and locking plate, so that, as the roller 12, descends in the slot B, the seat becomes fully inverted and the roller 10, remains at the forward end of said slot a, while the roller 12, engages against the downwardly and 95 rearwardly extended pointed end of the rib 4, as before described, thus rigidly locking the seat frame from movement in either direction except with the aid of the operator. The extended levers 38, on the locking arms 100 110 36, are then forced outwardly from the ends, releasing the ends of the foot-piece from engagement thereby, and permitting the operator to engage the forward end of the mattress frame section 23, to draw the mattress frame and bed outwardly. Outward draft on said section acts on the short section 24, and the second long section 21, to swing the same upwardly to the position shown in Fig. 3, with the effect of swinging 115 the first short section 19, upwardly to horizontal position, and thereby forcing the first long section 17, upwardly until the pivot pins 18, thereon engage in the upper horizontal part of the slot in said slotted bracket. The mattress frame is then straightened down, as shown in Fig. 2, the leg 39, (which is rigidly secured on each of the end members of the short sections 24) 120 125 supporting said short section, and thereby 130

the outer end of the second long section in the same horizontal plane with the sections 17 and 19, while the leg 28, at the outer end of the section 23, is projected downwardly 5 by the extending of the mattress frame, affording a rigid support for the structure as a whole. The foot piece, if not before, may now be turned upwardly.

Any desired resilient mattress fabric may 10 be employed on the respective mattress frame sections, it only being necessary to construct and dispose the same as to enable the same to bend readily or hinge in alinement with the axes of the hinge connections 15 for the various sections. The mattress 40, is secured in place thereon in any suitable manner, and being relatively thin, occupies but little space when folded. Preferably (though not necessarily) strong pulling 20 springs 41, are secured on the adjacent end of the long sections 21 and 23, and assist in closing the device as illustrated in Fig. 3. When it is desired to close the bed, the foot 25 piece is first turned inwardly upon the end of the mattress. The operator then slightly lifts the outer end of the mattress frame section 23, thus springing the joint afforded between the section 19, and second short section 21, and the springs now operate to 30 pull the three outer sections inwardly, the mattress frame sections bending automatically at each of the short sections, as illustrated in Fig. 3, and with the continued bending movement, the first long frame section 35 17, inclines downwardly and inwardly, with the supporting pins therefor sliding down the slot until the bed is folded in the position shown in Fig. 4, and the ends of the foot piece again engage beneath the 40 hooks 37, of the locking bars or latches 36, engaged on the seat frame. The seat frame may now be restored to normal position by pushing the same slightly inwardly and pressing downwardly at the front edge 45 thereof, thus reversing the operation of turning, as before described, permitting the roller 12, to travel up the cam slot B, in the cam and locking plate, while the roller 10, passes rearwardly along the slot a, and A, 50 until the roller 12, passes over and into the slot C, and thence downwardly to the normally locked position shown in Fig. 6.

I have described but a preferred form of 55 my invention. It is, of course, to be understood that various details of the construction may be varied, both as to the construction and the operation thereof. I therefore do not purpose limiting the patent granted on this application otherwise than necessitated by the prior art.

I claim as my invention:

1. A davenport embracing the end and back frame members, an invertible seat pivotally supported on the end frame members, a projecting bracket secured near each

70 rear corner thereof, a spring latch secured on each end of the seat, a mattress frame comprising a plurality of articulated alternate long and short sections one thereof pivotally engaged on said bracket and another section adapted to be engaged by said latch to support the mattress frame in folded position on the seat when the device 75 is closed, a fixed slotted tracking member governing the movement of one of said articulated sections, and springs secured to adjacent ends of said long sections to assist in closing said frame.

2. A davenport of the class described embracing an invertible seat, an articulated 80 sectional mattress frame foldable and wholly supported thereon, a spring latch rigidly secured on each end of the seat frame to move therewith and positively engaging to support the mattress frame on 85 said seat when the seat is reverted to normal position, resilient members fastened to adjacent ends of alternate frame sections to facilitate closing said frame, and a slotted guide member rigidly secured on said seat, 90 and positively engaging one portion of said articulated frame to guide the same.

3. In a davenport a foldable mattress frame, a foldable foot-piece pivotally supported in upright position on the outer extremity thereof when opened and adapted when folded inwardly to press upon the bedding, and spring latches positioned to engage the ends of said foot piece and acting thereby to lock the mattress frame in 100 folded relation when closed.

4. A device of the class described embracing an invertible seat frame, a spring latch secured on each end thereof to move therewith and projecting upwardly and centrally therefrom when the seat is inverted, a foldable mattress frame comprising articulated sections, means pivotally engaging one of said sections to the frame, and an inwardly foldable foot piece at the outer end 105 of the mattress frame, adapted for engagement by the spring latches when the mattress frame is closed, and affording means for supporting the mattress frame against the seat frame when the seat is reverted to 110 normal position.

5. In a davenport the end frame members, an inwardly facing cam and locking plate secured on each, and affording a bottom cam slot inclining downwardly toward the ends, forwardly and upwardly inclined cam slots communicating therein, a forwardly and upwardly inclined rib arranged between said inclined slots and extending to the first named slot, an invertible seat, a locking plate rigidly secured on each end thereof, and affording a downwardly directed hook at its forward end, a pivot pin secured on said plate near the middle of the seat end, and projecting into the first named 115 120 125 130

slot, a flanged roller thereon tracking in the slot, a locking pin in advance of the pivot pin, and positioned to engage beneath the end of said rib in either adjusted position 5 of the seat, said mechanisms being so adjusted relatively to each other that the locking pin passes upwardly and around said rib and returns to locking position beneath the end thereof in turning the seat upon the 10 pivot pin with the travel of the pivot pin from one to another of the ends of said bottom cam slot, and a mattress frame wholly supported upon the seat when folded and partly supported thereon when 15 extended.

6. In a davenport the end frame members, an inwardly facing cam and locking plate secured on each, and affording a bottom cam slot inclining downwardly toward the ends, 20 forwardly and upwardly inclined cam slots communicating therein, a forwardly and upwardly inclined rib arranged between said inclined slots and extending to the first named slot, an invertible seat, a locking 25 plate rigidly secured on each end thereof, and affording a downwardly directed hook at its forward end, a pivot pin secured on said plate near the middle of the seat end, and projecting into the first named slot, a 30 flanged roller thereon tracking in the slot, a locking pin in advance of the pivot pin, and positioned to engage beneath the end of said rib in either adjusted position of the seat, said mechanisms being so adjusted and dis- 35 posed relatively to each other that the locking pin passes upwardly and around said rib and returns to locking position beneath the end thereof in turning the seat upon the pivot pin, with the travel of the pivot pin 40 from one to the other of the ends of said bottom cam slots, a mattress frame wholly supported upon the seat when folded and partly supported thereon when extended, and a pin set in the cam and locking plate 45 and adapted for engagement by said hook when the seat is in normal position.

7. In a device of the class described a cam and locking plate having a longitudinally extended slot therein near one edge 50 thereof, upwardly and forwardly directed slots communicating therein, an inclined rib between said inclined slots and extending to the first named slot, and a pin or stop projecting from the face of said cam and locking plate at one end thereof.

8. In a device of the class described a cam and locking plate having a longitudinally extended slot therein near one edge thereof inclining downwardly at one end, 60 upwardly and forwardly directed slots communicating therein, an inclined rib between said inclined slots and extending to the first named slot, and a pin or stop projecting from the face of said cam and locking plate at one end thereof.

9. In a device of the class described a frame, a seat adjustable thereon, a pivot and locking plate adapted for engagement one at each end of the seat, a pivot secured thereon and projecting from the face thereof at substantially the center of the seat end, a flanged roller thereon, a locking pin engaged on said plate in advance of the pivot pin; a roller thereon, a cam and locking plate having cam slots therein to receive said rollers and to permit inversion of the seat on said pivot pin, said locking pin engaging beneath said cam in either of the adjusted positions of the seat, and a rigid stop afforded on each plate and adapted to interlock to hold the seat in one of its adjusted positions.

10. In a davenport of the class described, an articulated mattress frame, comprising alternate long and short sections articulated together to permit said mattress frame folding oppositely at the short sections, and rigid legs secured at the outer short section to support the same upon the floor.

11. A davenport of the class described embracing an invertible seat, an articulated mattress frame foldable on the seat when inverted and wholly supported thereon, and comprising articulated, alternate long and short sections, brackets projecting from the rear corners of said seat on which the first short mattress sections are pivoted unequally, a plate secured on the seat at each end thereof and having an inclined slot therein, a pin secured at each end of the inner long mattress section and engaging in the slots in said plates, legs rigidly secured at each end of the outer short mattress section, springs engaging adjacent ends of the long sections over said short sections and acting to assist the mattress frame in folding, and means locking the seat in either of its adjusted positions.

12. In a device of the rotary class described the invertible seat, a mattress frame comprising alternate long and short articulated sections, the first long section pivotally engaged upon the seat, springs engaging the adjacent ends of the long sections and acting to fold the second long section 110 inwardly on the first, and the outer long section inwardly on the second, a foot piece foldable inwardly on the bedding at the outer end the outer section, and spring latches carried on the seat adapted to engage said foot piece to hold the mattress frame section in folded relation when the seat is rotated to normal position.

13. A device of the class described embracing an articulated mattress frame comprising alternate long and short sections pivotally connected together to permit the respective sections of the mattress frame to fold oppositely at the short sections, rigid means secured on the outer of the short sec- 120

tions to support the same upon the floor when the mattress frame is extended for use, pivoted legs on the outer section of the mattress frame adapted to swing down-
5 wardly to support the outer end of the same upon the floor when the same is ex-
tended for use, and rigid means having
sliding engagement with the inner section of
the mattress frame to elevate and cause the
10 same to move rearwardly into an alined

position with the other sections when ex-
tended and to support said inner section in
position for use.

In testimony whereof I have hereunto
subscribed my name in the presence of two 15
subscribing witnesses.
